(57) **CLAIM**

The ornamental design for a modular towing connector, as shown and described.

DESCRIPTION

FIG. 1 is a lower-right, rear elevation perspective view of the modular towing connector in accordance with a first embodiment of the invention;

FIG. 2 is an upper-left, front elevation perspective view of the modular towing connector of FIG. 1;

FIG. 3 is a rear elevation view of the modular towing connector of FIG. 1;

FIG. 4 is a left side elevational of the modular towing connector of FIG. 1;

FIG. 5 is a front elevation view of the modular towing connector of FIG. 1;

FIG. 6 is a right side elevation view of the modular towing connector of FIG. 1;

FIG. 7 is a top elevation view of the modular towing connector of FIG. 1;

FIG. 8 is a bottom elevation view of the modular towing connector of FIG. 1;

FIG. 9 is a lower-right, rear elevation perspective view of the modular towing connector in accordance with a second embodiment of the invention;

FIG. 10 is an upper-left, front elevation perspective view of the modular towing connector of FIG. 9;

FIG. 11 is a rear elevation view of the modular towing connector of FIG. 9;

FIG. 12 is a left side elevational view of the modular towing connector of FIG. 9;

FIG. 13 is a front elevation view of the modular towing connector of FIG. 9;

FIG. 14 is a right side elevation view of the modular towing connector of FIG. 9;

FIG. 15 is a top elevation view of the modular towing connector of FIG. 9; and,

FIG. 16 is a bottom elevation view of the modular towing connector of FIG. 9.

The broken lines in the drawings are for illustrative purposes only and form no part of the claimed design

1 Claim, 16 Drawing Sheets
